UNITED STATES PATENT OFFICE.

JAMES J. MULLEN AND FRANCIS M. STAMBAUGH, OF ST. LOUIS, MISSOURI; SAID STAMBAUGH ASSIGNOR TO SAID MULLEN.

METAL-BENDING MACHINE.

Application filed January 7, 1927. Serial No. 159,589.

This invention relates to metal bending machines.

One object of the invention is to provide a practicable machine of novel construction for bending or folding a sheet metal plate so as to produce a corrugation or hollow rib on the plate provided with a closed end or closed ends.

Another object is to provide a machine 10 of novel construction that will produce symmetrical corrugations or hollow ribs on a metal plate, provided with closed ends that terminate within the marginal edges of the plate. Other objects and desirable 15 features of the invention will be hereinafter pointed out.

Figure 1 of the drawings is an end elevational view of our improved machine, showing the head of the machine in its 20 raised position.

Figure 2 is an end elevational view, showing the head of the machine depressed.

Figure 3 is a side elevational view of the machine showing the head raised.

25 Figure 4 is an enlarged vertical transverse sectional view, showing the male die member arranged in operative relationship with the female die members.

Figures 5 and 6 are perspective views 30 illustrating one form of sheet metal plate on which the machine is adapted to operate when the machine is used to produce a sheet metal member or article equipped with a plurality of corrugations or hollow ribs provided with closed ends, and arranged in parallel relation between abutting end sections of the plate that constitute end rims for the article.

Figure 7 is a perspective view of the plate 40 shown in Figures 5 and 6, after said plate has been bent or folded so as to produce corrugations thereon; and

Figures 8 and 9 are detail views, illustrating 45 how the male and female die members co-operate to produce a corrugation on the plate.

The machine herein illustrated is designed 50 primarily for use in producing a sheet metal member provided with straight, parallel corrugations or hollow ribs that have closed ends which terminate within opposed marginal edges of the plate from which the member is constructed, but we wish it to be understood that our invention is not 55 limited to a machine designed for this par-

ticular purpose, as one important feature of our invention consists of a novel means or mechanism for forming a corrugation on a metal plate, that extends throughout the entire length of the plate or only part way 60 the length of the plate. When the machine is used for producing a sheet metal member or article provided with a plurality of corrugations or hollow ribs that have closed ends which terminate within the marginal 65 edges of the plate from which the article is constructed, it is necessary to form longitudinally aligned notches 1 in the opposite ends of the plate, prior to introducing the plate into the machine to bend or fold it 70 so as to produce corrugations thereon. The end or ends of said corrugations are closed by portions 2 of the plate lying at the inner ends of the notches 1, said portions 2 being bent or shaped prior to the operation 75 of arranging the plate in the machine or while the plate is being bent to produce the ribs or corrugations. When a plate provided with pre-formed, angularly-disposed portions 2 is used in the machine, the intermediate portions of the plate lying between the longitudinally-aligned end notches 1 will be bent or folded progressively so as to produce corrugations or hollow ribs 80 13 on the plate that terminate some distance 85 inwardly from the ends of the plate and the angularly-disposed portions 2 of the plate will be moved into abutting relationship so as to form end closures for the corrugations. 90

Referring to the drawings which illustrate the preferred form of the invention, A designates a vertically-reciprocating head that moves towards and away from a stationary base plate B, said head and base plate having die members mounted on same which co-operate with each other at each downward stroke of the head to bend or fold the plate so as to produce a longitudinally-disposed corrugation or hollow rib 95 on the plate. The co-operating members that are used in this bending or folding operation can be constructed in various ways without departing from the spirit of our invention, but they will preferably consist 100 of an internal mandrel or male die member C and two rockable or oscillating female die members D arranged at opposite sides of said mandrel and so constructed and arranged that when the head A moves down- 105 110

wardly, said female die members D will rock inwardly and exert pressure on the plate in such a manner as to bend or fold the plate over the mandrel C, and thus produce a corrugation in the plate that conforms to the shape and dimensions of said mandrel, the rockable female die members D finally coming to rest in the position shown in Figure 4, wherein it will be seen that they virtually form a female die inside of which the mandrel C is arranged at the termination of the folding operation. On the succeeding upward stroke of the head A of the machine the rockable female die members D swing outwardly out of engagement with the corrugation just formed, and the male die member or mandrel C withdraws from the corrugation, thereby permitting the plate to be fed forwardly so as to bring into operative position the next portion of the plate which is to be bent or folded to produce a corrugation. In the machine herein shown the male die member C consists of a relatively long, straight element of substantially wedge shape in transverse cross section, and the female die members D consist of rockable wings or arms that are adapted to embrace said male die members, but said members can be of various shapes, depending upon the shape of the corrugations that are to be formed in the plate.

When the head of the machine is in its raised position, as shown in Figures 1 and 3, the plate π is sustained by a work support formed by horizontally-disposed members E arranged at opposite sides of the mandrel C and supported by springs F which hold the top surface of said members E flush or substantially so with the top edge of the mandrel C. During the first portion of the downward movement of the head A of the machine the female die members D remain separated or in the position shown in Figure 1, but after the inner edges 4 at the lower ends of said members have engaged the plate, said members D start to swing inwardly, thereby exerting pressure on the plate in a direction tending to clamp it firmly against the work sustaining members E and also to bend the plate downwardly over the mandrel C which exerts upward pressure on the underside of the plate, at about the time the female die members D start to swing inwardly. During the remainder of the downward stroke of the head A of the machine the female die members D continue to swing inwardly towards the mandrel C, and at about the time the head A has reached the end of its downward stroke, the plate will have been bent or folded over the mandrel C, thereby producing a corrugation or hollow rib on the plate that conforms to the cross-sectional shape of the mandrel. The springs F which support the

work sustaining members E are of such tension that they will permit said members E to recede or move downwardly under the influence of the downward pressure which the female die members D exert on the plate, but said springs are made strong enough to insure the plate being clamped tightly enough between the lower ends of the female die members D and the work sustaining members E to eliminate the possibility of the plate buckling or kinking during the folding operation. At the completion of the folding operation the head A of the machine moves upwardly, the female die members D swing outwardly out of engagement with the corrugation on the plate, and the work sustaining members E move upwardly under the influence of the springs F, and thus strip the plate from the mandrel C.

In the machine herein illustrated the internal mandrel or male die member C is carried by the base plate B of the machine and the rockable female die members D are carried by the reciprocating head A of the machine, so as to prevent scale or dirt from collecting in sufficient quantities in the cavity between the female die members D to interfere with the operation of the machine, but this is not essential, for if desired, the rockable female die members D can be carried by the base of the machine and the male die member or internal mandrel C can be carried by the reciprocating head of the machine.

The notches 1 in the ends of the plate π are of such width that in the operation of folding or bending the plate to produce a corrugation thereon, the adjacent sections 3 at the ends of the plate lying at opposite sides of the two notches which are in longitudinal alignment with the portion of the plate that is being folded, will move into abutting relationship, and thus co-operate to produce plain or uncorrugated portions at the ends of the plate which lie beyond the ends of the corrugation. The angularly-disposed portions 2 on the plate, previously referred to, are also proportioned and arranged so that in the operation of folding or bending the plate to produce a corrugation the two angularly-disposed portions 2 at each end of the part of the plate that is being folded will move into abutting relationship, and thus form closures for the ends of the corrugation.

It is important that the abutting end sections 3 of the plate lie in the same horizontal plane so that the edges of same will butt together, and it is also important that each pair of angularly-disposed portions 2 on the plate that constitute an end closure for a corrugation will be accurately aligned or butted together at the completion of the folding operation so that when the joints between said parts are closed or seamed by

a soldering, brazing or welding operation, the closed ends of the corrugation will be symmetrical and will merge into the portions of the plate which lie beyond the ends 5 of the corrugation. Accordingly, we prefer to arrange pressing devices G at the ends of the female die members D which are constructed so that they will engage the angularly-disposed portions 2 of the plate and 10 press them against the ends of the mandrel C, and will also engage the abutting end sections 3 of the plate and press them downwardly against stationary anvils H during the last portion of the downward stroke of 15 the head A of the machine, said pressing devices G operating to impart the final shape to the portions 2 of the plate that constitute end closures for the corrugation and also causing the co-operating abutting end 20 sections 3 of the plate to be brought into accurate alignment with each other. As shown in Figure 3, the anvils H are arranged so that they lie in the same horizontal plane as the work sustaining members E 25 after said members E have been moved downwardly by the pressure exerted on the same by the female die members carried by the head of the machine.

The rockable female die members D can 30 be constructed and operated in various ways, but in the machine herein illustrated said members are provided at their upper ends with longitudinally-disposed knuckles 5 that rock or oscillate in bearings 6 which are 35 detachably connected to members 7 carried by the reciprocating head of the machine. At one or both ends of each of the rockable die members D upwardly-projecting arms 40 are attached to said members, said arms being equipped with rollers 9 that co-operate with a stationary wedge or cam 10 to cause the die members D to swing inwardly when the head A of the machine moves downwardly. When the head A is in its elevated 45 position, as shown in Figure 1, the rollers 9 on the arms 8 are held pressed together by springs 11 attached to the die members D. During the first portion of the downward stroke of the head, i. e., prior to the time 50 the inner edges 4 of the lower ends of the female die members D engage the plate, said members remain in their separated position, shown in Figure 1, but in the succeeding portion of the downward movement of the head, the upper end of the wedge 10 passes 55 upwardly between the rollers 9, and thus rocks the arms 8 in a direction to move the die members D inwardly into the position shown in Figure 2. When the head A moves 60 upwardly the die members D swing outwardly out of engagement with the corrugation that has just been formed under the influence of the springs 11, and the springs F expand and move the work sustaining members E upwardly, thereby stripping the 65 corrugation from the mandrel C. In order that the time of operation of the rockable die members D may be accurately controlled or regulated, the wedge 10 is mounted on the base portion B of the machine in such a way 70 that it can be raised or lowered, the machine herein illustrated being provided with a holder 12 in which the wedge 10 is vertically adjustable.

One feature of our invention which we believe to be novel, is a sheet metal corrugated apparatus composed of an internal mandrel or male die member and a pair of co-operating rockable or oscillatingly mounted female die members, combined in such a way that the inward movement of said female die members towards the male die member, and the relative reciprocating movement of said male die member and female die members, produced by the downward movement of the head of the machine, causes the plate to be bent or folded over said male die member without liability of kinking or buckling the plate, the plate being sustained during the folding operation by a work support that 80 presses the plate against the lower ends of the rockable female die members and which recedes or moves in a direction to permit the male die member to enter the cavity 85 between the female die members. So far as this feature of our invention is concerned it is immaterial whether it is embodied in a machine that is used to form an open-ended corrugation which extends throughout the entire length of the plate, or a closed end 90 corrugation which extends only part way the length of the plate. When such an apparatus is used to produce a corrugation provided with closed ends, however, it is preferably to add to same a means, such as the 95 pressing devices G and anvils H that will bend or impart the final shape to portions of the plate that constitutes end closures for the corrugation and also flatten down or line up the divided end sections of the plate 100 located beyond the ends of the corrugations.

Having thus described our invention, what we claim as new and desire to secure by Letters Patent is:

1. A metal binding machine for progressively bending a plate to form hollow ribs or corrugations thereon, said machine comprising a work support that is adapted to sustain a flat plate, a male die member that is adapted to engage the side of the plate that contacts with said work support, co-operating rockable female die members adapted to engage the opposite side of said plate, means for bodily moving the female die members towards the male die member and the work support, thereby causing said female die members to hold the plate firmly against the work support, and means for moving said female die members after they have engaged the plate, so as to bend 110

the plate over the male die member while portions of the plate are frictionally engaged by the work support and the female die members.

- 5 2. A metal bending machine, comprising a pair of female die members and an opposed male die member shaped so as to co-operate with each other to progressively bend or fold a flat plate to produce corrugations thereon, means for producing relative reciprocating movement between said male die member and female die members to produce an initial bend or fold in the plate positioned between said male member and female members, means for moving the female die members inwardly or towards each other during said relative reciprocating movement so as to complete the bend or fold in the plate, and means for causing the plate to exert sufficient frictional pressure on the ends of said female die members during the inward movement of said members to prevent the plate from buckling.
- 10 3. A metal bending machine, comprising a male die member and a pair of rockable or oscillating female die members adapted to be arranged at opposite sides of a plate that is to be bent to produce a corrugation on the plate, means for producing relative reciprocating movement between said male die member and female die members, means for swinging the female die members inwardly towards the male die member during said relative movement, and work engaging devices that hold the plate against the ends of said female die members during the entire inward movement of said female die members, arranged to yield or move in a direction to permit the male die member to enter the cavity between said female die members.
- 15 4. A metal bending machine, comprising a yielding work engaging means that is adapted to contact with one side of a flat plate that is to be bent to form a corrugation thereon, a pair of rockable female die engaging members adapted to engage the opposite side of the plate and press it against said means, means for producing relative reciprocating movement between said female die members and said work engaging means, an internal mandrel arranged stationary with respect to said work engaging means, with its upper end positioned flush or substantially so with the plate supporting surface of said means at the beginning of the cycle of operations of the machine, said mandrel being adapted to co-operate with said female die members to form an initial bend in the plate, and means for rocking said female die members during said relative reciprocating movement.
- 20 5. A metal bending machine for progressively forming corrugations in a flat metal plate, comprising a reciprocating head, a stationary base, a male die member carried

by one of said elements and having a cross-sectional shape that corresponds to the cross-sectional shape of the corrugations formed on the plate, a pair of rockable female die members carried by the other elements and adapted to swing inwardly towards said male die member to bend or fold the plate over said male die member, yielding work engaging devices arranged adjacent said male die member and adapted to hold the plate in a horizontal position and clamped against the ends of said female die members during the inward movement of same, and means for rocking said female die members inwardly when said head is moved towards said base.

6. A metal bending machine, comprising a reciprocating head, a stationary base, a male die member carried by said base, a pair of rockable female die members carried by said head, a horizontally disposed, yielding work support arranged substantially flush with the top edge of said male die member and adapted to hold the work against said female die members, arms attached to said female die members, and a stationary device that co-operates with said arms to rock said female die members when said head reciprocates.

7. A metal bending machine, comprising a reciprocating head, a stationary base, a male die member carried by one of said elements, a pair of rockable female die members carried by the other element, yielding work engaging devices arranged longitudinally of said male die member at opposite sides of said male die element and adapted to hold the work against the ends of said female die member, arms attached to said female die members and provided with rollers, a wedge or cam arranged to pass between said rollers and thus cause said female die members to rock when the head reciprocates, and a means for separating said female die members or moving them outwardly.

8. A metal bending machine, comprising a reciprocating head, a stationary base, a pair of rockable female die members carried by one of said elements, a horizontally-disposed, yielding work engaging device that is adapted to engage a flat plate and cause it to be held in sliding frictional engagement with the ends of said female die members when said members are functioning, a means that co-operates with said female die members to produce an initial longitudinal fold in the plate after the ends of said female die members have engaged the plate, and means for causing said female die members to rock in a direction to complete the fold in the plate so as to produce a longitudinal corrugation on the plate, when said head reciprocates.

9. A metal bending machine, comprising

an internal mandrel, means for folding or bending an intermediate portion of a plate over said mandrel so as to form a corrugation on the plate which terminates within 5 the marginal edges of the plate, means for causing portions of said plate to be disposed so as to form end closures for the corrugation, and means for holding the end sections of the plate, lying beyond the ends of the 10 corrugations in a flat condition during the operation of bending the plate.

10. A metal bending machine adapted to operate on a plate having longitudinally-aligned notches, means for bending or folding 15 the intermediate portion of the plate lying between said notches so as to produce a corrugation on the plate and also cause portions at the inner ends of said notches to be arranged in position to form end closures for 20 the corrugation, and pressing devices that act on the portions of the plate located beyond the ends of the corrugations for imparting the final shape to said parts during the corrugating operation.

25. 11. A metal bending machine, adapted to operate on a metal plate provided with longitudinally-aligned end notches that have angularly-disposed portions at their inner ends, means for folding or bending the intermediate portion of the plate lying between 30 said notches and causing the end sections of the plate and also the angularly-disposed portions at the inner ends of said notches to move into abutting relationship, and pressing devices that act on said angularly-disposed portions and abutting end sections during 35 the corrugating operation.

12. A metal bending machine, comprising a reciprocating head, a stationary base, rockable female die members carried by one of 40 said elements and provided at their ends with pressing devices for the purpose described, a male die member carried by the other element, yieldingly supported work 45 engaging devices arranged longitudinally of said male die member at opposite sides of said male die member and adapted to hold the work pressed tightly against the ends of said female die members during a portion 50 of the stroke of said head, means for rocking said female die members inwardly during

a portion of the stroke of the head, and anvils with which said pressing devices co-operate.

13. A machine that is adapted to be used to form corrugations on a flat metal plate 55 provided in opposed edges with longitudinally-aligned notches, said machine comprising co-operating die members arranged at opposite sides of the plate, means for causing said die members to coact with each other to bend the intermediate portion of the plate lying between a pair of said notches into a corrugation provided with end closures formed by abutting extensions on the side walls of said corrugation, and means 60 for preventing the end sections of the plate lying between said notches from wrinkling during the operation of forming said corrugation.

14. A machine that is adapted to be used 70 to progressively form parallel corrugations or ribs on a metal plate, said machine comprising a yielding, horizontally-disposed work support that is adapted to receive a flat metal plate provided in opposed edges 75 with longitudinally-aligned notches, a male die member of less length than the width of the plate that is adapted to serve as a mandrel over which said plate is bent or folded, rockable female die members arranged in 80 parallel relation with said male die member at opposite sides of same, means for producing relative vertical movement between said male die member and female die members and for causing said female die members to 85 frictionally clamp the plate against said work support and also swing inwardly towards said male die member, thereby bending the intermediate portion of the plate lying between a pair of notches into a corrugation and also causing the end sections 90 of the plate to move into abutting relationship.

15. A machine of the kind described in 95 claim 14, in which the female die members have portions that cause integral parts of the plate located at the ends of the side walls of the corrugation to be formed into symmetrical end closures for the corrugation.
